FEEDING DEVICE FOR CHAFF CUTTING
MACHINES AND THE LIKELudwig Eirich and Joseph Eirich, Hardheim,
GermanyApplication November 12, 1930, Serial No. 495,213
In Germany November 18, 1929

3 Claims. (Cl. 146—110)

This invention relates to a feeding mechanism for fodder-cutting machines and the like, in which two endless conveying bands are arranged in a frame one above the other and in which the lower of the two conveying bands is rigidly mounted in the side walls of the machine frame and the upper conveying band is mounted in a pivoted bearing frame in the interior of the machine frame casing of the mechanism so as to be 10 movable up and down relative to the lower band.

It is an object of the invention to construct a feeding mechanism of the kind set forth, in which the upper conveyor band is mounted on a bearing frame which is mounted at one end on pivots on 15 the walls of the machine frame casing surrounding the mechanism in such a manner that the said bearing frame may oscillate, whereby the variation in the thickness of the fodder will cause the bearing frame to raise and lower.

20 A form of construction of the conveying device is illustrated by way of example in the accompanying drawings in which:

Fig. 1 is a vertical section through the conveying device on line 1—1 of Fig. 2.

25 Fig. 2 is a top plan view partly in section on line 2—2 of Fig. 1.

Fig. 3 is a side elevation of the conveying device.

Fig. 4 is a vertical section on line 4—4 of Fig. 1.

30 Fig. 5 is an end view illustrating the connection between the driving gear and the endless bands.

The upper endless band, which in general is 35 designated by A, is carried by a bearing frame b which with the band as a whole oscillates at changing thickness of the string of material to be cut around bolts c of the two side walls r of the machine frame R. The bolts c are arranged in the lower portion of the bearing frame b in proximity to the pinion d, so that the upper band A is adapted to move tongs-like relative to the lower band. The two carrying bolts c take up a considerable portion of the weight of the bearing frame b and of the band, so that this band oscillates easily up and down at the discharge end C. In order to prevent cut material dropping through the oblong holes e of the side walls and to proceed 45 into the interior of the chain links, sealing discs f are mounted on the shaft g on the mouthpiece side C, which discs cover the oblong holes e at any position of the band and prevent cut material passing through said holes. A straight-edged plate h is rigidly fixed to two angular flaps h₁ of the oscillatable bearing frame b, said plate serving as a press plate. This plate does not extend

outwardly as far as the mouthpiece plate h₂. As the press plate h is further distant from the two pivot bolts c than the shaft g of the upper band A, it has a longer stroke than the shaft g. The press plate h, rigidly fixed on the bearing frame, 5 obviously exerts a greater pressure on the string of fodder when this string is thin than when the same is thick. The press plate h, representing so-to-say an upper lip, which rests on and holds the thin string of fodder in the proximity of the 10 knife blades, located closely adjacent the discharge end C of the feed mechanism in known manner, so that the string of fodder cannot yield under the shifting cutting pressure of the knife. When the press plate is ascending and when it is 15 in its highest extreme position, the delivered string of fodder can slightly expand in upward direction. For breakable material, for instance dry wheat straw, clover hay, chips of sugar cane, 20 wood chips or brushwood sticks this reduction of pressure close to the knife is material if very short chaff has to be cut, as this preferable reduction enables the string to be rapidly and uniformly delivered and further the production of a 25 chaff of equal length, preventing the breaking of the upper string portion and the vertical positioning of the upper layers of the string, which frequently happens at the moment when it is being discharged.

In the form of construction shown and described, driving pinions d having six teeth are 30 mounted in the upper and lower endless bands A and B. At their opposite ends the bands run over rollers i loosely rotating on the shafts g and m. By altering the diameter of these rollers i 35 the band can be tightly stretched. Two levers o, keyed on the projecting ends of the shaft g of the band A and carrying short, toothed arc-shaped pieces on the end facing the mouthpiece side, serve for the parallel guiding of the upper 40 endless band A and for regulating the pressure of the same. The arc-shaped pieces have teeth in the outer edge. The teeth of the two levers o engage with the internal teeth of arc-shaped pieces p₁ fixed on the machine frame wall. At 45 the ascending and descending movement of the band A the weight-loaded lever p, which is fixed on the short lever o, is oscillated owing to the meshing toothed arc pieces o and p₁. The shaft g therefore carries out the same movement as 50 the two toothed levers o.

The lower endless band B is not supported by a separate bearing frame but its shafts k and m are journaled in bores of the side walls. Sliding bars n for the carrying side of the endless band 55

may be arranged directly on the side walls of the machine. The bearing frame *b* is fitted in the interior of the band *A* with sliding plates *n* for the lower and upper sides of the band.

5 The two bands *A* and *B* are driven by a spur wheel gearing. The driving spur wheel *u* is loosely mounted on the bolt *c* around which the bearing frame *b* oscillates and it meshes on the one hand with the spur wheel *r* on the driving shaft of the driving pinion *d* for the upper endless band *A* and drives on the other hand through the intermediary of an intermediate wheel *s* a spur wheel *t* on the shaft *k* of the pinion *d* for the lower band *B*.

10 15 We claim:

1. A feeding mechanism comprising in combination a main frame, pivot bolts in the side walls of said main frame, two endless bands one above the other, the lower band being stationary mounted in said main frame and the upper band being movably mounted in said main frame, a bearing frame for said upper endless band oscillatably mounted on said pivot bolts, a driving pinion for each of said endless bands, a driving gear on the shaft of one of said pinions for driving the latter, said driving gear meshing with a gear loosely mounted on one of said pivot bolts, said loosely mounted gear meshing with intermediate gears adapted to drive the other driving pinion.

20 25 30 2. A feeding mechanism comprising in combi-

nation a main frame having side walls, an arc-shaped piece having teeth on its inner surface fixed on the side walls of said frame, two endless bands arranged the one above the other, the upper band resting in a bearing frame, said bearing frame being pivoted between the side walls of the main frame, a shaft for the upper movable band journaled in the main frame so that one end projects, a weighted lever on the projecting end of said shaft, and an arc-shaped piece having teeth on its outer edge on said lever to mesh with the teeth of said first-mentioned arc-shaped piece.

3. A feeding mechanism comprising, a main frame having enclosing walls, said frame being provided with elongated openings, a pair of endless feeding bands one above the other, the upper band being supported on a bearing frame, said bearing frame being rotatably mounted on pivots in the walls of the main frame, sealing discs adjacent the elongated openings in the main frame to close said openings, said discs being movable with said bearing frame, said bearing frame being pivoted to a weighted lever, said lever being provided with an arcuate toothed end, and an arcuate toothed rack on the main frame and engaged with the toothed end of the lever, whereby upon raising and lowering of the lever the upper band is oscillated.
